UNITED STATES PATENT OFFICE.

JOHN E. BELL, OF NEW YORK, N. Y., ASSIGNOR TO THE BABCOCK & WILCOX COMPANY,
OF NEW YORK, N. Y., A CORPORATION OF NEW JERSEY.

WATER-TUBE BOILER.

1,141,520.

Specification of Letters Patent. Patented June 1, 1915.

Application filed December 26, 1905. Serial No. 293,170.

To all whom it may concern:

Be it known that I, JOHN E. BELL, of New York, county and State of New York, have invented a new and useful Improvement in 5 Water-Tube Boilers, of which the following is a full, clear, and exact description, reference being had to the accompanying drawings, forming part of this specification, in which—

10 Figure 1 is a front view of a battery of boilers embodying my invention, one boiler being shown in end elevation and the other in vertical section; Fig. 2 is a longitudinal vertical section; and Figs. 3 and 4 are views 15 similar to Fig. 2, but showing other forms of the invention.

My invention relates to water tube boilers, and more particularly to those of the horizontal type, wherein the tubes extend in a 20 general horizontal direction, usually between the horizontal plane and 45 degrees thereto. Owing to the restriction of flow through the tubes and headers, it has been necessary to limit the height of the boiler 25 and the amount of the heating surface, for the reason that if the height of the boiler is increased beyond certain limits, the flow is restricted to such an extent as to endanger the lower tubes.

30 In my pending application, Serial No. 286,184, filed November 7, 1905, I have described and claimed broadly means for overcoming these difficulties, consisting in providing the lower set of tubes with a direct 35 connection at one or both ends to an upper steam and water space or drum, and connecting the upper set or sets of tubes to a water space or drum, independently of the connection for the lower set, whereby a 40 rapid circulation is provided through the lower tubes which are nearest the furnace, and most liable to be burned out. This arrangement also provides for a very large increase in the height of the boiler, since a 45 number of sets of tubes, may, by means of the independent connections to the water spaces or chambers be superimposed one above another.

One object of my present invention is to

simplify and improve the manner of connecting the lower tubes with the upper steam and water space, and to thereby provide for more convenient access to the upper tubes. To this end the headers of the lower tubes are directly connected at one 50 or both ends with an intermediate or sub-drum or chamber, which in turn has a single connection with each of the upper steam and water chambers or drums, these single connections being so arranged as not to interfere with free access to the upper tubes. 60

A further object of my invention is to provide for the use of superheaters in this type of boiler, so arranged that the volume of hot gases from the furnace will come in 65 full contact therewith after first passing over a number of water tubes. To this end, I arrange the superheater between the water tubes, preferably in the first pass of the gases, such superheater occupying less space 70 than the full length of the tubes, and being readily accessible and removable.

My invention also consists in the novel construction and arrangement and combination of parts, all substantially as hereinafter 75 described and pointed out in the appended claims.

In the drawings, referring to the form shown in Figs. 1, 2, and 3, I show a horizontal water tube boiler having a lower set 80 of inclined tubes 2 connected at the ends by the headers 3 and 4 which may be of any usual or ordinary form. The headers 3 are directly connected, by means of short nipples or connections 5, with a sub-drum or 85 chamber 6 which extends transversely of the boiler, and has a single separate connection 7 with each of the steam and water drums 8, 9 and 10. These drums 8, 9 and 10 are shown as extending longitudinally of the 90 boiler, but they may however, extend transversely of the boiler and be located above either end of it. In Figs. 1, 2 and 3, the drum 6 and connections 7 are shown as being at the upper ends of the tubes. 11 and 95 12 designate two upper sets of tubes which are shown as being parallel to the lower tubes, the tubes 11 being connected to the

headers 11^a, and the tubes 12 to the headers 12^a. The headers 11^a at the rear end are connected to the header 4 by the vertical tubes or nipples 13; the rear headers 11^a and 12^a are connected by the nipples 14; and the rear headers 12^a are connected to the saddles of the upper steam and water drums by the pipes 15. At the front end, the headers 11^a and 12^a are connected by the nipples 16, and the headers 12^a are connected to the upper steam and water drum by the nipples 17. The tubes 11 and 12 are shorter than the tubes 2, and the vertical connections 7 are placed in the space at the rear of the tubes 11 and 12.

10 I have shown two sets of grates 18 and 19 extending from the front and rear walls 20 and 21 to a bridge wall 22 arranged transversely at an intermediate point. Fire doors 23 are provided at both ends of the setting, the grates extending underneath substantially the whole of the boiler. The fire doors may, however, be placed at one or both ends of the setting, and the grates may 25 extend beneath any desired portion or portions of the heating surface.

The baffling may be of any desirable type. In the form shown in Figs. 1, 2, 3 and 4, I have shown the lower horizontally extending 30 arch or baffle 24 below the lower row of water tubes, and two vertically extending series of baffles 25 and 26 arranged to form three up and down passes of the gas. The baffle 25 has the jog or off-set 27 which 35 serves to contract the upper portion of the first pass and the lower portion of the second pass, such jog or off-set being between the two upper sets of tubes. This proportions the gas passages to the temperature 40 and volume of the gases which contract as they cool, and is a desirable, although not a necessary feature of the invention.

The space between the vertical connections 7 is sufficiently large to permit easy 45 access to the rear headers 11^a and 12^a.

In the operation of the boiler, the water 50 and steam in the lower tubes flows into the headers 3 and thence into the intermediate or sub-drum 6, and from such drum to the main steam and water drums, where the steam is released. In this manner, a rapid circulation is provided in the lower set of tubes, such circulation being independent of that through the upper tubes.

55 In the form shown in Figs. 1, 2 and 3, separate connections are not employed at the rear end of the boiler for the tubes 2, 11 and 12. In the form shown in Fig. 3, however, an intermediate or sub-drum 6^a similar 60 to the drum 6 and connected to the lower rear header 4 by nipples 4^a is employed. This drum 6^a is connected to the header 11^a of the tubes 11 by nipples 11^b, and is provided with a supply connection or connections 6^c to the main steam and water drums.

The arrangement is otherwise the same as that first described, except that I have shown a slightly different arrangement of grates 18^a and 19^a, these grates being set at a greater angle.

70 As the upper sets of tubes are subject to the action of the furnace gases, after they have parted with a portion of their heat, I can stack the rows of tubes of these upper sets above each other, to any desired height, 75 within practical limits, without danger of burning out the lower tubes.

28 designates a superheater which is shown as interposed between the tubes 2 and the tubes 11. This superheater is 80 shown as being of the U-tube form, but I may employ a superheater of any suitable type. In the form shown in Figs. 1, 2, and 3, this superheater is located at the front end of the boiler with the tubes extending 85 at right angles to the water tubes, and in the first pass of the gases.

29 indicates the inlet or supply connections for the superheater 6 connected to the several drums 8, 9 and 10, as best shown in 90 Fig. 2.

30 is the outlet pipe connection for the superheater.

In the form shown in Fig. 4, the superheater 28^a is shown as being located between the lower tubes 2 and the tubes 11 at the rear end of the furnace. In this form, the baffling consists of a lower baffle or arch 31, two vertical series of baffles 32 and 33, and a horizontally arranged baffle 32' extending from the front wall of the furnace to the bottom of the baffle 32. The vertical baffles 32 and 33 are not, however, directly vertical, but the two series of baffles are inclined toward each other at their lower ends, so that there is provided a contraction of the gas passages in the direction of the flow of the gases by means of which the same result is obtained as in the construction first described. By reason of the arrangement of baffling shown in this form, the first pass of the gases is along the whole length of the lower tubes 2, thence upwardly over the superheater and the rear end portions of the tubes 11 and 12, thence 105 downwardly between the baffles 32 and 33, and thence upwardly at the front of the boiler. The superheater tubes in this form are shown as extending parallel with the water tubes, the inlet connections being 110 shown at 34 and the outlet connection at 35.

In this form the intermediate drum 6 is omitted and the headers 3 are connected with the saddles of the drums 8, 9 and 10 by the vertical pipes 7^a. 115 Instead of a single lower set or bank of tubes connected to an intermediate or sub-drum, it is evident that several sets may be provided, each with an intermediate or sub-drum connected to the main steam and 120

water drum. The upper sets of tubes, instead of being parallel with the lower ones, may be inclined at a different angle, or reversely inclined. The furnace may be fired from one or both ends, and the grate may extend below any part or all of the boiler, and many other variations may be made in the form and arrangement of the boiler, pipes and connections without departing 10 from my invention.

The advantages of my invention result from the use of the intermediate chamber or drum, at one or both ends of the boiler, whereby the number of connections to the 15 upper drums is reduced, and access to the upper tubes is provided; also from the location and arrangement of the superheater between the tubes in a manner to be readily accessible, and occupying a minimum of 20 space, thereby increasing the compactness of the boiler. By placing the superheater at a higher or lower point in the boiler, or by changing the arrangement of the baffles, the degree of superheating may be varied.

25 I claim:—

1. In a steam boiler, the combination with upper and lower banks of substantially longitudinally disposed tubes, a steam and water drum, said banks being provided 30 with separate connections for conducting the steam generated therein directly to the steam and water drum, means for causing the products of combustion to make serial passes transversely over said tubes, and a superheater located between the banks.

2. In a steam boiler, the combination with upper and lower banks of substantially longitudinally disposed tubes, a steam and water drum, said banks being provided 40 with separate connections for conducting the steam generated therein directly to the steam and water drum, substantially vertical baffles extending transversely of the tubes for causing the products of combustion 45 to have an upward and downward passage across the tubes, and a superheater located in the up-passage of the gases.

3. In a horizontal water tube boiler, the combination with an upper set of substantially 50 vertical end headers or boxes, of a plurality of inclined water tubes connecting the same, a lower set of substantially vertical end headers or boxes, one of the same being disposed in vertical alinement with the corresponding upper header, the other being arranged in a different plane the corresponding upper header, inclined water tubes connecting the lower headers, a substantially horizontal steam and water chamber located above both 55 sets of headers, an intermediate or sub-drum located between the upper and lower headers that are in vertical alinement and connected to both, a sub-drum located over the lower header that is out of vertical alinement with the upper header and con-

nected to said lower header, a direct connection between said latter sub-drum and the steam and water chamber, and an independent direct connection between the corresponding upper header and the steam and 70 water chamber.

4. In a steam boiler, the combination with longitudinally disposed upper and lower banks of tubes, of a transverse pass for the products of combustion having an 75 upper restricted portion, and a superheater located in the lower larger portion of said pass.

5. In a steam boiler, the combination with longitudinally disposed upper and 80 lower banks of tubes, of a transverse upward pass for the products of combustion, across the tubes having an upper restricted portion, and a downward transverse pass across the tubes communicating with the 85 upward pass and having a restricted lower portion.

6. In a steam boiler, the combination with longitudinally disposed upper and lower banks of tubes, of a transverse upward pass 90 for the products of combustion, across the tubes having an upper restricted portion, a downward transverse pass across the tubes communicating with the upward pass and having a restricted lower portion, and a 95 superheater located in the lower larger portion of the upward pass.

7. In a horizontal water tube boiler, the combination with upper and lower banks of water tubes, of a furnace located below 100 the same, transversely disposed baffles to cause the products of combustion to flow upwardly across the tubes, and a superheater arranged in one of the passes formed by the baffles, said pass being constricted 105 above the furnace.

8. In a horizontal water tube boiler, the combination with upper and lower sets of water tubes spaced apart, of a furnace located below the set of tubes, a baffle extending transversely of both sets of tubes to produce a pass across the same, and a superheater arranged in the pass between the sets of tubes, said pass being constricted 110 above the tubes.

9. In a horizontal water tube boiler, the combination with a substantially horizontal set of water tubes, of a furnace located below the same, oppositely extending transversely disposed baffles arranged across the tubes and producing up and down passes, one of said baffles having an offset to produce a constriction in the first pass and also in the second pass, and a superheater arranged in the first pass and above the furnace. 120

10. In a steam boiler, the combination with a lower bank of tubes, of an upper bank of tubes shorter than the same, upper and lower headers for the banks, the upper 125

header at one end being out of alinement with the lower header at the same end, an upwardly extending baffle across both banks in spaced relation to the said offset headers, 5 and a superheater in the pass formed between the baffle and the set of headers at one end.

In testimony whereof, I have hereunto set my hand.

JOHN E. BELL.
